UNITED STATES PATENT OFFICE.

FRANK E. CROMPTON, OF BROOKLYN, NEW YORK, ASSIGNOR TO SIGNATURE COMPANY, OF NEW YORK, N. Y., A CORPORATION OF NEW YORK.

BINDER BOARD.

Application filed June 1, 1923. Serial No. 642,781.

To all whom it may concern:

Be it known that I, FRANK E. CROMPTON, a citizen of the United States, residing at Brooklyn, county of Kings, and State of New York, have invented certain new and useful Improvements in Binder Boards, of which the following is a specification.

In its broadest scope, my invention comprises mechanism for effecting a combined registry along two edges of a plurality of overlapping sheets or documents.

In the preferred embodiment of the invention it is combined with a binder board having the general character shown in my prior U. S. Patent No. 1,350,141, dated August 17th, 1920. According to the practice set forth in said patent, sheets or documents to be written upon are located in a temporary binder with respect to indicator fingers by which said sheets or documents are arranged in a predetermined order corresponding to that of the separately pivoted pens of a multiple writing machine. In sheets or documents so arranged the thickness of the pack varies according to the number of sheets or documents superposed one upon another at different points in the series. Hence the separately pivoted pens of the multiple writing machine are displayed in varying degrees depending upon the different thicknesses of the pack underlying the several sheets or documents which are being inscribed at the same time. As a result, when the sheets or documents are arranged in a temporary binder in the manner disclosed in my above identified patent, and fed into position in a multiple writing machine, the inscriptions made thereon by the several pens will be more or less displaced with respect to the positions they were intended to occupy. To overcome this objection, constitutes the primary object of my invention.

One of the objects of the present invention is to provide an improved construction, combination and arrangement of parts in a binding board whereby the documents as they are placed in the binder, are automatically adjusted relatively to each other in amounts depending upon the thickness of the pack at those places to be written upon by several pens. Other and further objects will appear in the specification and be pointed out in the appended claims, reference be-

ing had to the accompanying drawings which exemplify my invention in a preferred embodiment.

Figure 1 is a top plan view of a binder board constructed in accordance with the principles of the present invention, parts being broken away;

Figure 2 is a front elevation of the same;

Figure 3 is a section on an enlarged scale on the line 3—3, Figure 1;

Figure 4 is a fragmentary diagrammatic front elevation on an enlarged scale showing the relative displacement between the registering gages at opposite ends of the binder;

Figure 5 is a perspective view of the register rail and the relatively movable side register gages pivotally mounted thereon;

Figure 6 is a diagrammatic front view of the variable registering mechanism detached; and

Figure 7 is a diagrammatic front elevation of the corresponding series of pens of the multiple writing machine.

Referring more particularly to the drawings, the binder board comprises a bed plate 1, provided along its rear edge with a plurality of bearing brackets 2. Within the bearing brackets 2 is journaled an oscillatory shaft 3. Mounted on the shaft 3 adjacent to one end thereof is a hand lever 4 which is adjustably connected to the shaft 3 by means of a radial arm 5 fixedly connected to the shaft 3 and adjustment screws 6 mounted in lugs 7 on the hand lever 4 on opposite sides of the arm 5. The adjustment of the screws 7 will thus effect an angular displacement of the hand lever 4 with respect to other parts keyed to the oscillatory shaft 3. Keyed to the shaft 3 intermediate of the spaced bearing lugs of each of the brackets 2, is a radial arm 8. Secured to the outer ends of the radial arm 8 is a binder operating rail 9 which as shown in Figure 2, is provided along its lower edge with a series of notches 10. Said notches 10 accommodate forwardly presented ends 11^a of a series of clips or grippers 11 (see Figure 1) of the temporary binder now to be described. Each of the grippers 11 is secured by rivets 12 to a binder strip 13, said binder strip being of suitable length to fit between laterally spaced socket abutments 14 mounted on the bed plate 1 of the binder

100
105

board. The binder strip 13 is provided with a longitudinal series of holes 15 (only one of said holes being shown in Figure 3) to accommodate a series of upwardly projecting pins 16 which are mounted in a series along the rear edge of the bed plate 1, and constitute front edge gages for a plurality of sheets or documents.

It will be seen from the foregoing description that whenever the handle lever 4 is depressed as shown in Figures 1 and 2, the spring clip 17 is adapted to releasably engage a laterally projecting pin 18 carried by the handle lever 4. In this position of the gripper operating rail 9, the gripper strip 13 will be forced down onto the bed plate 1, while the upwardly presented pins 16 project upwardly into engagement with the forwardly presented ends of the spring clips 11, thus holding said spring clips in raised positions to permit the documents to be inserted thereunder and serving as registry gages for their front edges. Referring now more especially to Figures 3, 4, and 5, the documents registering device comprises a transverse bar 20 provided along its rear face with slotted lugs 21 which as shown in Figure 3 adapt the bar 20 to be mounted along the upper edge of the gripper operating rail 9. Suitable set screws 22 are provided for securing the lugs 21 to the gripper operating rail 9. Oscillatably mounted upon the forwardly presented face of the bar 20 are a plurality of side registering gages each comprising a flat plate 23 pivotally mounted on a stud 24 and provided with an arcuate slot 25. A second stud 26 which is threaded into the transverse bar 20, extends thru the arcuate slot 25 and permits a limited angular movement to the side register gage. Said gage is provided with a forwardly presented flat-plate portion 27 against which the edge of a document is made to abut when inserted into the binder. The lower edge of said flat-plate portion 27 is beveled upwardly as shown at 28 in Figures 3 and 5 toward the direction from which sheets or documents are introduced thereunder. Said beveled lower edges are thus adapted by a camming operation to raise the side edge gages 27 and thus to adjust the gaging surfaces thereof laterally in amounts depending upon the thicknesses of sheets or documents thereunder. In this way the correspondingly elevated pen points will be brought into registry with the same writing line on each sheet or document. As shown in Figure 4, the pivoted gage 27 at the right end of transverse bar 20, is in direct contact with the bed plate 1 of the binder board. The side register gage 27 is therefore disposed in normal vertical position since there are no underlying documents. At the other end of the transverse bar, according to Figure 4, the registering

gage 27 rests upon ten thicknesses of paper and in consequence is subjected to a lateral displacement due to its upward displacement caused by the underlying documents. The amount of this lateral displacement is represented by the distance between the dot and dash lines 27^a and 27^b, said lines representing respectively the position of the gage plate 27 when there is nothing between it and the bed plate 1 and the laterally displaced position of the gaging surface thereof when elevated as shown in Figure 4. By an inspection of this figure it will be obvious that the next document to be superposed upon the pack to the left of the gage plate 27, will be adjusted laterally to a degree corresponding to the writing position of the corresponding pen of the multiple writing machine. A diagrammatic representation of the gage plates and writing pens corresponding thereto are shown in Figures 6 and 7. Thus in Figure 6 the gage plates 27 corresponding to the first five and the tenth side register gages shown in Figure 5 are represented. In Figure 7, the corresponding writing pens 30 of a multiple writing machine are shown pivotally mounted at 31 upon a tubular bar or rod 32, said writing pens 30 being displaced in greater degree toward the left according to the graded thicknesses of documents arranged below them. It will be understood therefore that the side registry position of each of said gages is variable depending upon the thickness of documents thereunder.

I claim:

1. In a binder board, means for operating a binder to receive documents and for holding said documents in a predetermined arrangement, and document registering means into engagement with which the side edges of said documents are moved as they are placed within the binder.
2. In a binder board, means for operating a binder to receive documents and for holding said documents in a predetermined arrangement, and side registering gages slidably engaging said documents for locating them as they are placed within the binder.
3. In a binder board, means for operating a binder to receive documents and for holding said documents in a predetermined arrangement, and side registering gages for locating said documents as they are placed within the binder, said side registering gages operating to automatically adjust the positions of the documents to correspond to the thicknesses of documents underlying the respective gages.
4. In a binder board, the combination with a bed plate adapted to receive a document binder, of means for opening the grippers of said binder and permitting them to close on a group of documents in

- pre-arranged order, and side registering gages slidably engaging the lateral edges of said documents for automatically adjusting the lateral positions of said documents 5 with respect to each other.
5. In a binder board, the combination with a bed plate adapted to receive a document binder, of means for opening the grippers of said binder and permitting them to close on a series of documents in pre-arranged order, and side registering gages for locating said documents in the binder, each of said side registering gages being adapted to be displaced by the introduction of a document therebeneath and by said displacement to adjust the position of a document registered thereby.
6. In a binder board, the combination with a bed plate adapted to receive a document binder, of means for opening the grippers of said binder and permitting them to close on a group of documents in pre-arranged order, and side registering gages laterally contacting with said documents in the binder, each of said side registering gages being automatically adjustable by a prior registered document to correct the position of a document to be registered by said gage.
- 30 7. In a binder board, a bed plate, an oscillatory shaft mounted on said bed plate, a rail carried by said oscillatory shaft and cooperating with said bed plate for opening and closing the grippers of a document binder, and a plurality of side registering gages mounted on said rail for locating a series of documents as they are moved into position within the binder.
8. In a binder board, a bed plate, an oscillatory shaft mounted on said bed plate, a rail carried by said oscillatory shaft and cooperating with said bed plate for opening and closing the grippers of a document binder, and a plurality of side registering gages mounted on said rail for locating a series of documents within the binder, said side registering gages being provided with registering surfaces adjustable laterally to correspond to different thicknesses of documents underlying said side registering gages.
- 50 9. In a binder board, a bed plate for holding a document binder, a gage bar mounted to oscillate about an axis on said bed plate, side registering gages oscillatably mounted on said gage bar, and means for opening and closing the grippers of said document binder.
- 60 10. In a binder board, an oscillatory shaft, a rail mounted on said oscillatory shaft and adapted to be moved into and out of position to open the grippers of a document binder, and side registering gages carried by said rail and oscillatable about separate axes, each of said side registering gages being provided with a gaging surface which is adjusted laterally by the oscillation of said gage.
11. In a binder board, a bed plate provided with upwardly presented pins arranged to correspond to the grippers of a document binder, a binder operating rail oscillatable about an axis and adapted to depress the binder down on to said bed plate against the pressure of said grippers acting against said pins, and side registering gages mounted on said rail for individually locating the documents to be placed in said binder.
12. In a binder board, a rock shaft, a binder operating rail mounted on said rock shaft, a gage bar reciprocable on said rail, and a plurality of side registering gages oscillatably mounted on said gage bar and adapted to be displaced in variable degree, depending upon the thickness of documents therebeneath, each of said gages being provided with a laterally adjustable gaging surface for automatically correcting the position of the document located thereby.
13. In mechanism for registering a plurality of sheets, the combination with means for registering the front edges of said sheets, of means abutting the lateral edges of said sheets for side registering the same.
14. In mechanism of the character described, the combination with means for registering the front edges of a plurality of overlapping sheets, of separately movable means for registering the side edges of said sheets.
15. In mechanism of the character described, the combination with means for registering the front edges of a plurality of overlapping sheets, of laterally spaced side registry gages movable separately for gaging the side edges of said sheets in variable positions depending upon the thicknesses of documents underlying said gages.
16. In mechanism of the character described, the combination with means for registering the front edges of a plurality of overlapping sheets, of laterally spaced side registry gages for separately gaging the side edges of said sheets, said side registry gages being laterally adjusted by displacement due to the varying thickness of the documents underlying the several side registry gages.
17. In mechanism of the character described, means for front registering a plurality of overlapping sheets, and separately movable side registering gages resting upon said sheets and having registering surfaces adjustable laterally by vertical displacement due to the variable thickness of the sheets underlying said gages.
18. The combination with a binder board, of a document binder, and a plurality of independently movable side edge gages

adapted to locate said documents as they are placed in said binder and to laterally adjust them to correspond to thicknesses of documents below said gages.

19. The combination with a binder board, of a document binder, and side edge gages for documents to be mounted in said binder, said gages being movable independently of each other to permit the introduction thereunder of variable thicknesses of said documents and adjustable laterally by said upward movements to vary the location of said documents in said binder depending upon the thickness of said documents below said side edge gages.

20. The combination with a binder board, of a document binder, and side edge gages for documents to be mounted in said binder, said gages being movable independently of each other to permit the introduction thereunder of variable thicknesses of said documents and adjustable laterally by said upward movements to vary the location of said documents in said binder depending upon the thickness of said documents.

ments below said side edge gages, said side edge gages comprising plates having the lower edges bevelled upwardly toward the direction from which said documents are introduced thereunder.

21. The combination with a binder for a plurality of sheets to be bound, of a support therefor, and sheet-gaging members movably mounted upon said support for respectively locating said sheets within said binder, each of said sheet gaging members having a gaging surface and a gage positioning surface.

22. The combination with a binder for a plurality of documents to be bound together, of a support therefor, and gage plates movably mounted on said support, said gage plates being provided with cam-shaped bearing edges adapted to be displaced by some documents and gaging surfaces for positioning other documents according to the displacement caused by the first mentioned documents.

FRANK E. CROMPTON.
